(57) **CLAIM**

The ornamental design for a desktop light therapy device, as shown and described.

DESCRIPTION

FIG. 1 is a front perspective view of a desktop light therapy device showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of a portion indicated with “9” in FIG. 2.

FIG. 10 is an enlarged view of a portion indicated with “10” in FIG. 5.

FIG. 11 is an enlarged view of a portion indicated with “11” in FIG. 7.

FIG. 12 is a perspective view of the use state of a desktop light therapy device.

FIG. 13 is another perspective view of the use state of a desktop light therapy device; and,

FIG. 14 is another perspective view of the use state of a desktop light therapy device.

The evenly spaced broken lines illustrate portions of the desktop light therapy device that form no part of the claimed design. The dot-dash broken lines in FIGS. 2, 5, 7, and 9-11 are included to show a partially enlarged view only and form no part of the claimed design.

1 Claim, 14 Drawing Sheets
